Application June 6, 1944, Serial No. 539,006

9 Claims. (Cl. 260—668)

1

This invention relates to the preparation of aromatic hydrocarbons from hydrocarbon mixtures and particularly from naphtha hydrocarbon mixtures.

The invention involves separation of aromatic hydrocarbons, particularly aromatics of higher molecular weight than toluene, from hydrocarbon mixtures containing them and converting the separated hydrocarbons into aromatic hydrocarbons of improved character for motor fuel manufacture. In accordance with the invention, aromatic hydrocarbons, such as xylenes or aromatic concentrates separated from naphtha, are subjected to the action of an aluminum halide catalyst so as to effect reforming or transforming into aromatics which have a greater blending value for gasoline.

More specifically, an aromatic hydrocarbon such as ortho xylene which has a blending I. M. E. P. (indicated mean effective pressure) value of 0, is isomerized to give a blending value of 320 which is to be compared with a similar blending value of about 244 for iso-octane. Likewise, an aromatic concentrate, boiling within the range of about 212-300° F., separated from hydroformed naphtha and having a blending value of about 170 may be subjected to the action of an isomerizing catalyst so as to produce a product having a blending value of about 231.

An effective catalyst for this purpose is aluminum halide-hydrocarbon complex such as obtained by reacting aluminum chloride with kerosene in the presence of hydrogen chloride at a temperature of about 200-250° F., so as to produce a complex having a heat of hydrolysis of around 290-330 small calories per gram of complex.

The aromatic hydrocarbons are subjected to the action of such complex catalyst in the presence of hydrogen halide promoter at temperatures ranging from 100-300° F. and preferably about 180-220° F. such that the hydrocarbons undergo reforming, in which isomerization is one of the principal reactions involved in increasing the blending value of the aromatic hydrocarbons undergoing treatment.

A complex catalyst of the foregoing character is effective as a solvent for extracting aromatic hydrocarbons from mixtures containing them and, therefore, may be used to selectively extract aromatic hydrocarbons from paraffin hydrocarbons so as to obtain an aromatic concentrate. The dissolved aromatic hydrocarbons can be separated or displaced from the complex by washing with a saturated hydrocarbon boiling either substantially below or above the dissolved aromatic hydrocarbons. By using as the wash solvent a hydrocarbon boiling outside the range of the aromatic hydrocarbons, it is possible to separate

2

the aromatic from the wash solvent by distillation.

If it is not required to isolate the treated aromatics, the wash solvent may have a boiling range within that of the treated aromatics.

The wash solvent may be a paraffin hydrocarbon, mixture of paraffins, a naphthene hydrocarbon, mixture of naphthalenes, or a mixture of paraffin and naphthene hydrocarbons.

The invention thus contemplates employing the aluminum halide-hydrocarbon complex in the dual capacity of reforming catalyst and extraction solvent. Thus, aromatic hydrocarbons may be extracted from a naphtha mixture and the resulting extract, comprising aromatics dissolved in complex, may then be exposed to conversion conditions so that the dissolved aromatic hydrocarbons undergo isomerization or other reforming conversion reaction. Thereafter the converted hydrocarbons may be separated from the complex either by distillation or by washing with a suitable wash solvent.

It is contemplated that the extraction and conversion reactions may be carried out simultaneously and in a continuous manner and in a single reaction tower. On the other hand, the extraction and conversion reactions may be carried out in separate zones as will be hereinafter described.

Figure 1 of the accompanying drawings illustrates a method of operation wherein aromatic hydrocarbons are continuously subjected to contact with the catalyst under conversion conditions and the resulting aromatic products continuously displaced from the reaction zone either with or without washing with a paraffin hydrocarbon such as pentane.

Figure 2 illustrates a method of flow wherein an aromatic concentrate is prepared by extraction with complex liquid in an extraction zone and the resulting extract solution passed to a separate reaction zone to effect conversion of dissolved aromatic hydrocarbons.

Figure 3 illustrates a three-stage process wherein an aromatic concentrate is obtained in an extract stage, the resulting solution of aromatics in complex liquid passed to a reaction stage and from there to a final stage wherein the aromatic products are washed from the complex.

Referring now to Fig. 1, an aromatic hydrocarbon such as ortho xylene is conducted from a source not shown through a pipe 1 and passed through a heater or heat exchanger 2 wherein it is heated to a temperature of about 180-210° F. The heated stream is then conducted through a pipe 3 to the lower portion of a vertical reaction tower 4.

The tower 4 contains a column of aluminum chloride-hydrocarbon complex having a heat of hydrolysis of about 320 calories per gram of com-

plex. Advantageously, the complex liquid column is maintained in a substantially static condition, without mechanical agitation, and may have a height ranging from about 10 to 25 feet.

The feed hydrocarbons are injected into the bottom of the liquid catalyst column in dispersed form and the dispersed hydrocarbons tend to rise through the catalyst column by difference in density.

The catalyst column is maintained at the foregoing reaction temperature of about 180-210° F. effective for converting ortho xylene into meta and para xylenes as well as other valuable aromatic hydrocarbons.

A small amount of hydrogen chloride promoter is continuously added from a source not shown and introduced through a pipe 7 leading to the pipe 3.

The aromatic hydrocarbons are thus exposed to the catalyst in the presence of the promoter which latter may amount to from 0.5 to 5.0% or from about 2.0 to 3.0% by weight of the aromatic hydrocarbon undergoing treatment. Make-up aluminum chloride may be added intermittently or continuously in small amount so as to maintain the catalyst liquid at the predetermined level of activity. The aluminum chloride may be added as a solution or as a suspension in a portion of the aromatic feed stream.

When a wash solvent is used, a paraffin hydrocarbon, such as normal pentane, is continuously recycled through the system as will be described and enters the reactor 4 through a pipe 8 communicating with the pipe 3. The pentane is introduced to the reactor in the proportion of about 1 to 3 parts by volume of pentane to one volume of aromatic feed hydrocarbon. The pentane stream also may be used for introducing the make-up aluminum chloride.

The aromatic hydrocarbons and pentane rise through the catalyst column and accumulate in the top of the reaction vessel.

The paraffin hydrocarbon may undergo some conversion but the extent of such conversion is limited due to the inhibiting effect of the aromatic hydrocarbons present. In other words, aromatic hydrocarbons substantially inhibit isomerization of normal paraffins under the conditions prevailing within the reactor 4.

The effluent hydrocarbon stream containing converted aromatics is continuously drawn off through a pipe 10 to a fractionator or stripper 11 wherein the promoter is stripped from the hydrocarbons. The promoter gas is removed through a pipe 12 and recycled all or in part through a pipe 13 communicating with the previously mentioned pipe 3.

The hydrocarbons from which the promoter has been removed are conducted through a pipe 14 to a fractionator 15 wherein a pentane fraction is continuously removed as a distillate fraction through a pipe 16 and cooler 17. The pentane fraction so removed is conducted through a pipe 18 and may be recycled all or in part through the previously mentioned pipe 8. However in the absence of the wash solvent, the fractionator 15 may be by-passed by conducting the hydrocarbon stream from the stripper 11 through pipe 14a to the fractionator 21.

The residual hydrocarbon fraction comprising aromatics is conducted from the fractionator 15 through a pipe 20, or from the stripper 11 through pipe 14a to a fractionator 21 wherein it may be separated into fractions as desired; for example, it may be separated into a distillate fraction

which is removed through a pipe 22 and a residual fraction comprising high boiling hydrocarbons which is removed through a pipe 23. This latter fraction may be recycled through a pipe 24 to the reactor 4.

A continuous tower operation as illustrated in Figure 1 may be carried out without the wash solvent, since the treated aromatics will rise through the column of liquid by difference in density. The complex catalyst is thus maintained saturated with aromatics and even though saturated, retains substantial activity for isomerizing and reforming aromatic feed hydrocarbons. The saturated complex contains approximately equal volumes of free aromatics and complex.

Referring now to Figure 2, a naphtha mixture or a mixture of aromatics and paraffins is conducted from a source not shown through a pipe 30 and a heat exchanger 31 wherein it is brought to a temperature of about 70-100° F.

The mixture then flows through a pipe 32 to the bottom of an extraction tower 33 wherein it is subjected to countercurrent contact with a body of aluminum chloride-hydrocarbon complex characterized by having a heat of hydrolysis of about 290 to 330 calories per gram of complex. This complex may be used complex such as is drawn off from the subsequent conversion reaction. It is introduced into the top of the tower through a pipe 34.

As the feed hydrocarbons rise through the tower 33, aromatic constituents are dissolved in the complex. The undissolved non-aromatic hydrocarbons rise to the top of the tower and are continuously removed therefrom through a pipe 35 and cooler 36.

The complex containing dissolved aromatic hydrocarbons is continuously drawn off from the bottom of the extractor through a pipe 37 and conducted through an exchanger or heater 38 wherein it is brought to a temperature of about 200° F. The heated solution is then passed into a reaction tower 40. In the reactor 40, the aromatic hydrocarbons thus remain in contact with the catalyst in the presence of promoter for a short period of time as in the case of the reactor 4 of Figure 1 so that the aromatic hydrocarbons undergo conversion.

A stream of paraffin hydrocarbon such as pentane is likewise introduced continuously to the reactor 40 so as to subject the complex to continuous washing and thereby effect displacement of the aromatic hydrocarbon product from the complex.

The hydrocarbon products are continuously drawn off from the top of the reactor through a pipe 41.

The pipe 41 advantageously leads to a fractionating system such as is illustrated in Figure 1. The fractionating system may comprise a stripper for stripping the promoter which is then recycled through a pipe 13 as in Figure 1. Likewise, the paraffin hydrocarbon is separated from the products and recycled through a pipe 8.

Referring to Figure 3, a hydrocarbon mixture containing aromatics is drawn from a zone not shown through a pipe 50 and heat exchanger 51. The heated mixture then passes into the bottom of an extraction tower 52 wherein it is subjected to countercurrent contact with a body of complex liquid as in the case of extraction tower 33 of Figure 2.

Temperature conditions are maintained so as to dissolve the aromatic hydrocarbons and thus

extract them from the non-aromatic hydrocarbons. The latter are continuously discharged from the top of the tower through a pipe 53 and cooler 54.

The resulting solution of aromatics in complex is drawn off from the bottom of the tower 52 through a pipe 55 to a reaction vessel 56. Hydrogen chloride promoter may be introduced from a source not shown through a pipe 57.

The reaction vessel 56 is maintained at an elevated temperature adapted to effect isomerization of aromatic hydrocarbons. The products of conversion, including catalyst, are continuously drawn off through the pipe 57 to a wash tower 58 wherein the mixture of complex catalyst and aromatic hydrocarbons is subjected to countercurrent contact with a body of paraffin hydrocarbons such as pentane. Thus, the complex mixture enters the upper portion of the wash tower 58 while the stream of normal pentane is continuously introduced to the lower portion thereof through pipe 59 in the proportion of about 1 to 3 volumes per volume of complex mixture.

The washing is effected at a temperature of about 100-150° F. so as to continuously displace aromatic hydrocarbon products from the complex catalyst.

The aromatic products are continuously discharged through a pipe 60 leading to a fractionating system such as described in Figure 1.

The washed complex substantially free from aromatics is drawn off through a pipe 61 and recycled all or in part through a pipe 62 leading to the top of the extractor 52. Some of the complex may be recycled directly through a branch pipe 63 to the reactor 56.

In order to maintain the activity of the complex catalyst, additional aluminum halide is added to the system through a pipe 64, such addition being made in somewhat the same manner as has been described in connection with Figure 1.

Provision may be made for recycling recovered promoter and wash solvent also as described in Figure 1.

Example I

A quantity of ortho xylene was charged to a reaction vessel, together with aluminum chloride-hydrocarbon complex in the proportion of 2 volumes of complex to 1 volume of hydrocarbon. Hydrogen chloride was added to the extent of 2% by weight of the total charge. The resulting mixture was maintained at a temperature of 210° F. and under pressure ranging from 43 to 70 pounds for a period of about 30 minutes. The complex catalyst was characterized by having a heat of hydrolysis of about 320 calories per gram.

The hydrocarbons were separated from the catalyst, and that portion free from C₅ and lower hydrocarbons was found to have the following composition:

Per cent by volume	
Hydrocarbons boiling below benzene	7
Benzene	4
Toluene	30
Meta and para xylenes, and ethyl benzene	31
Ortho xylene	8
C ₉ H ₁₂	10
Residue	10

¹ Apparently principally mesitylene

Example II

A quantity of ethyl benzene was charged to a reaction vessel, together with an aluminum chloride-hydrocarbon complex in the same pro-

portions as in Example I. The complex catalyst in this case had a heat of hydrolysis of about 298 calories per gram. The reaction was carried out in the presence of the same amount of the promoter at a temperature of 180° F. for a period of 30 minutes, the pressure ranging from 12 to about 16 pounds per square inch gauge.

The hydrocarbons were separated from the complex and the portion free from C₅ and lower molecular weight hydrocarbons had the following composition:

Per cent by volume	
Hydrocarbons boiling below benzene	8
Benzene	27
Toluene	11
Meta and para xylenes, and ethyl benzene	36
Ortho xylene	0
C ₉ H ₁₂	8
Residue	10

¹ Apparently all ethyl benzene

Example III

In this example a xylene concentrate having the following volume per cent composition was treated:

Per cent	
Toluene	2
Meta and para xylenes, ethyl benzene	69
Ortho xylene	21
Residue	8

This concentrate was mixed with complex of about the same character and in the same proportions as Example II. The reaction was carried out in the presence of a similar amount of promoter at a temperature of 210° F. for 30 minutes, the pressure ranging from about 20 to 31 pounds. The liquid products after removal of C₅ and lower hydrocarbons were of the following composition:

Per cent by volume	
Hydrocarbons boiling below benzene	8
Benzene	4
Toluene	23
Meta and para xylenes, and ethyl benzene	28
Ortho xylene	6
C ₉ H ₁₂	20
Residue	11

¹ Apparently principally mesitylene

In each of the foregoing examples the hydrocarbon products were separated from the complex by distillation at reduced pressure. It will be observed that in Example I the ortho xylene was isomerized to produce a substantial yield of a fraction comprising meta and para xylenes and ethyl benzene. In addition, the C₉ fraction apparently consisted principally of mesitylene.

It will be noted in the case of Example III that the ortho xylene content of the concentrate was reduced from 21 to 6% with the formation of benzene, toluene, meta and para xylenes and mesitylene, etc.

In the following example ortho xylene was treated with a complex catalyst under substantially the same conditions as used in Example I. At the end of the reaction, the reaction mixture of catalyst and hydrocarbons was subjected to extraction with normal pentane at a temperature of about 70° F. so as to separate the aromatic hydrocarbons from the complex catalyst. The separated hydrocarbons after removal of C₅ and lower hydrocarbons had the following composition:

Per cent by volume

Hydrocarbons boiling below benzene	11
Benzene	0
Toluene	20
Meta and para xylenes, and ethyl benzene	5
Ortho xylene	38
C ₉ H ₁₂	9
Residue	16
	6

Mention has been made of using aluminum chloride complex as the catalyst. However, it is contemplated that other aluminum halide isomerization catalysts such as aluminum bromide may also be used. Other hydrogen halide promoters besides hydrogen chloride may be used. Also other wash solvents besides normal pentane may be employed. Such other solvents may comprise liquified normally gaseous paraffin hydrocarbons or normally liquid hydrocarbons of higher molecular weight than pentane. Organic halides such as CCl₄ and CHCl₃ may be used as wash solvents.

Reaction temperatures of about 210° F. have been mentioned in the examples but it is contemplated that other temperatures may be employed, depending upon the activity of the catalyst, the character of the aromatic hydrocarbons undergoing treatment, and the extent of conversion desired. Thus, temperatures ranging from room temperature up to 300° F. may be employed, although temperatures ranging from 180 to about 220° F. are preferred.

The complex catalyst may have a heat of hydrolysis ranging from about 270 to 350 small calories per gram of complex, although a heat of hydrolysis in the range of about 290 to 330 is preferred. The activity of the catalyst should be such that the effluent stream of hydrocarbons will be substantially free from aluminum halide.

A reaction time of 30 minutes has been referred to in the examples, but a reaction time substantially below this may be used in a continuous flow system in which case the hydrocarbon residence within the reaction tower may be a matter of several minutes.

Complex catalyst will form in situ as a result of reaction between added aluminum halide and a small proportion of the aromatics undergoing treatment. Therefore, the rate of halide addition is controlled by observing the heat of hydrolysis of the complex catalyst from time to time during continued operation. Provision is made for withdrawal of a small portion of used complex from the reaction tower. Advantageously, used complex is withdrawn from an upper portion of the tower while make-up aluminum halide is added to the lower portion. Provision is also made for adequate space in the top of the reaction tower to effect disengagement between the hydrocarbon phase and the catalyst phase.

Thus, while complex formed by reacting with kerosene has been mentioned at the outset, nevertheless, it is contemplated that the complex employed in the system during continued operation may consist essentially of that formed by reaction between the halide and aromatics. Sufficient aluminum halide is added to the system to maintain the complex at the desired level of activity, i. e., having a heat of hydrolysis in the range about 290-330 calories.

It is also contemplated that provision may be made for effecting the extraction steps of Figs. 2 and 3 in the presence of a small amount of

promoter sufficient to prevent the complex from becoming too viscous.

The term "reforming" as used herein is contemplated as including reactions other than isomerization such as cracking, alkylation, alkyl exchange, etc. These reactions may occur simultaneously with isomerization, although isomerization is regarded as a principal reaction.

Obviously many modifications and variations of the invention as hereinbefore set forth may be made without departing from the spirit and scope thereof, and therefore only such limitations should be imposed as are indicated in the appended claims.

I claim:

1. A process for improving the blending value of an aromatic-rich naphtha by isomerization of aromatic constituents which comprises subjecting a fraction of said naphtha boiling in the range of about 212 to 300° F. to contact with an aluminum halide-hydrocarbon complex isomerizing catalyst having a heat of hydrolysis in the range of about 270 to 350 calories, and effecting said contact for a short period of time at a temperature in the range about 180 to 300° F. in the presence of a small amount of hydrogen halide such that aromatic hydrocarbons contained therein undergo isomerization to a substantial extent.

2. A process for preparing aromatic hydrocarbons of improved blending value by isomerization for the manufacture of motor fuel which comprises separating from naphtha a fraction rich in xylene and aromatics of higher molecular weight than toluene, subjecting said fraction to contact with an aluminum halide-hydrocarbon complex isomerizing catalyst having a heat of hydrolysis in the range of about 290 to 330 calories and effecting said contact for a short period of time at a temperature in the range about 180 to 220° F. in the presence of a small amount of hydrogen halide such that aromatic hydrocarbons undergo isomerization to a substantial extent.

3. A continuous process for isomerizing aromatic hydrocarbons of higher molecular weight than toluene which comprises continuously injecting said aromatic hydrocarbons into the lower portion of a vertical column of aluminum chloride-hydrocarbon complex catalyst liquid having a heat of hydrolysis in the range of about 270 to 350 calories, dispersing the injected hydrocarbons upwardly through the column in the presence of hydrogen halide at a temperature in the range of about 180 to 300° F. such that substantial isomerization occurs and continuously removing from the top of the column a hydrocarbon stream containing isomerized aromatic hydrocarbons.

4. A continuous process for isomerizing aromatic hydrocarbons of higher molecular weight than toluene which comprises continuously injecting said aromatic hydrocarbons into the lower portion of a vertical column of aluminum chloride-hydrocarbon complex catalyst liquid having a heat of hydrolysis in the range of about 270 to 350 calories, dispersing the injected hydrocarbons upwardly through the column in the presence of hydrogen halide at a temperature in the range of about 180 to 300° F., simultaneously dispersing upwardly through the column a low boiling saturated hydrocarbon so as to facilitate displacement of aromatics from the complex catalyst, and continuously removing from the upper portion of the column a hydrocarbon stream containing isomerized aromatic hydrocarbons.

5. A continuous process for isomerizing aromatic hydrocarbons of higher molecular weight than toluene which comprises extracting naphtha containing said aromatic hydrocarbons with aluminum halide-hydrocarbon complex having a heat of hydrolysis in the range of about 270 to 350 calories, forming a solution of aromatics in the complex, subjecting said solution in the presence of hydrogen halide to elevated temperature in the range 180 to 300° F. for a few minutes time such that the complex effects substantial isomerization of aromatic hydrocarbons, washing resulting complex containing dissolved isomerized hydrocarbons with a low molecular weight saturated hydrocarbon so that aromatic hydrocarbons are displaced therefrom and removing the displaced hydrocarbons.

6. A continuous process for isomerizing aromatic hydrocarbons of higher molecular weight than toluene which comprises passing a naphtha fraction rich in said aromatics and containing paraffinic hydrocarbons in countercurrent contact in an extraction zone with a body of aluminum halide-hydrocarbon complex having a heat of hydrolysis in a predetermined range of about 270 to 350 calories, effecting said contact at a temperature such that aromatics are dissolved in said complex in preference to paraffins, discharging undissolved paraffins, passing resulting solution of aromatics in complex to a reaction zone, subjecting it therein to a temperature in the range 180 to 300° F. in the presence of a small amount of hydrogen halide for a period of time ranging from several up to about 30 minutes such that substantial isomerization of said aromatics occurs, passing the so-treated mixture of hydrocarbons and catalyst to a separating zone, subjecting said mixture therein to countercurrent contact with a low boiling saturated hydrocarbon at a temperature in the range of about 100 to 150° F. such that isomerized aromatics are displaced from said mixture, separately discharging displaced hydrocarbons and complex catalyst from the separating zone, recycling discharged catalyst to said extraction zone and supplying make-up aluminum halide to the extraction zone to maintain the complex therein at said predetermined range.

7. The process according to claim 6 in which

said low boiling saturated hydrocarbon is normal pentane.

8. A continuous process for isomerizing aromatic hydrocarbons of higher molecular weight than toluene which comprises extracting naphtha containing said aromatic hydrocarbons with aluminum chloride-hydrocarbon complex having a heat of hydrolysis in the range of about 270 to 350 calories, forming a solution of aromatics in the complex, subjecting said solution in the presence of hydrogen halide to elevated temperature in the range 180 to 300° F. for a few minutes time such that the complex effects substantial isomerization of aromatic hydrocarbons, washing resulting complex containing dissolved isomerized hydrocarbons with a low molecular weight saturated hydrocarbon so that aromatic hydrocarbons are displaced therefrom and removing the displaced hydrocarbons.

9. A continuous process for isomerizing aromatic hydrocarbons of higher molecular weight than toluene which comprises passing a naphtha fraction containing aromatic and paraffinic hydrocarbons in countercurrent contact in an extraction zone with a body of aluminum chloride-hydrocarbon complex having a heat of hydrolysis in a predetermined range of about 270 to 350 calories, effecting said contact at a temperature such that aromatics are dissolved in said complex in preference to paraffins, discharging undissolved paraffins, passing resulting solution of aromatics in complex to a reaction zone, subjecting it therein to a temperature in the range about 180 to 300° F. in the presence of a small amount of hydrogen halide for a short period of time such that substantial isomerization of said aromatics occurs, passing the so-treated mixture of hydrocarbons and catalyst to a separating zone, subjecting said mixture therein to countercurrent contact with a low boiling saturated hydrocarbon at a temperature in the range of about 100 to 150° F. such that isomerized aromatics are displaced from said mixture, separately discharging displaced hydrocarbons and complex catalyst from the separating zone, recycling discharged catalyst to said extraction zone and supplying make-up aluminum chloride to the extraction zone to maintain the complex therein at said predetermined range.
